UNITED STATES PATENT OFFICE.

SAMUEL J. SEELY, OF BROOKLYN, NEW YORK.

IMPROVEMENT IN MACHINES FOR BENDING CORRUGATED SHEET METAL.

Specification forming part of Letters Patent No. 37,308, dated January 6, 1863.

To all whom it may concern:

Be it known that I, SAMUEL J. SEELY, of Brooklyn, in the county of Kings and State of New York, have invented a new and useful improvement in machines for bending corrugated sheet metal into cylinders which are corrugated around their circumference; and I do hereby declare that the following is a full, clear, and exact description of the same, reference being had to the accompanying drawings, forming part of this specification, in which—

Figure 1 is a side elevation and partial section of my improved machine. Fig. 2 is a vertical transverse section of the same. Fig. 3 is a vertical longitudinal section of the same. Fig. 4 is a corrugated sheet of metal, which is to be bent into the form of a cylinder by my machine. Fig. 5 is the same sheet as bent into cylinder form by my machine.

Similar letters of reference in the several figures indicate corresponding parts.

The main object of my invention is to manufacture by machinery the cylinder or body of corrugated sheet-metal casks, and thus meet the heavy demand for such casks, and at the same time reduce the cost of the same. To attain these results I have organized a roller-die which matches the corrugations of a previously-corrugated sheet, and, as the sheet is drawn through, it bends it gradually until it assumes the proper cylinder form. The three rollers composing the roller-die are set so as to bend the sheet at all parts to a segment of a given circle, and the several segments united necessarily constitute a full circle, and this circle is the desired cylinder form for the cask-body. My roller-die has a rotary motion in all of its parts, and the motion in one part is in concert with another part, and the motion of all the parts or rollers is positive by means of equal gear-wheels. The corrugations around one part or roller of the die mesh with the corrugations around another part or roller of the die, and the three rollers thus mesh together and each bites upon the corrugated metal sheet during the bending operation. My die is also capable of being diminished or increased in capacity, and thus bend corrugated sheets which have deep or shallow undulations.

The nature of my invention may be said to consist in bending sheet metal which has been previously corrugated into the form of a cyl-

inder which is corrugated around its circumference by means of an organized machine, which consists of three adjustable rollers having corrugated circumferential surfaces, said surfaces meshing into one another and also revolving in concert and with a positive and uniform motion.

To enable others skilled in the art to make and use my invention, I will proceed to describe its construction and operation.

A represent two strong end standards bolted firmly to a horizontal bed-piece or cross-tie, B. These standards with the tie constitute a simple substantial frame.

C is a feeding-table arranged on the front of the standards.

D D' D² represent three rollers with corrugations or grooves around their circumference. These rollers are of equal diameter, and are arranged within the frame, so that two of them are on the same horizontal plane and the other above them and directly over the valley formed between them, as represented. The boxes s, in which the shafts of these rollers turn, are arranged in different parts of a slot, t, of inverted-T form, said slot providing for three boxes. There is a slot of this character in each of the end standards of the frame, and in the same the boxes are adjusted by means of set-screws E F G. The rollers D D' D² may be solid with the shafts or axes on which they revolve; but I prefer to make them up of a shaft and a series of ring-flanges of V or other similar form in their radial section from center to circumference, as represented at a. These flanges are placed side by side one another on the shaft, and alternately form a groove and a tongue. The top roller should have two more flanges and one more groove than the lower rollers, and the flanges of the upper rollers should be deep enough to fill the grooves of the lower rollers, or very nearly so, and so also should the flanges of the lower rollers match the grooves of the upper roller. When the rollers are in operation on the sheet of metal, the flanges of all the rollers bite upon it. When the sheet of metal is being inserted between the rollers, the flanges of the respective rollers are not in perfect meshing position; but after the sheet is inserted they are moved to that position by adjusting the shafts of the rollers. The extent of the depth of entrance of the respective flanges into the respective

grooves of the several rollers is controlled or regulated by the set-screws E F G. If it is desired to bend sheets having a sharp corrugation, the rollers are moved up closer together by the set-screws; but if it is desired to bend sheets having a blunt corrugation, the rollers are moved farther apart. The flanges are confined on the shafts by collars, one of which collars is constructed with a nut, e, which fits a screw-thread, e, of the shafts, and thus binds the flanges together. It is desirable to have the rollers made of separated flanges, for if one of the flanges should be injured, its place can be filled by a perfect one. This is not the case with the rollers which have the flanges a part of the shaft. By providing the strong retaining-screws E E at the ends of the top roller any desired twist at one end of the sheet of metal may be imparted during the bending of it into the cylinder form by simply setting one end of this roller higher than its other end. The rollers are all geared together by cog-wheels I I I of equal diameters, and with teeth long enough to allow the necessary adjustments to the rollers. The power is transmitted from a belt-shaft, J, to the rollers by means of a pinion, K, which gears with a large spur-wheel, L, of the front lower roller.

To bend a sheet of corrugated metal, such as shown in Fig. 4, into the form shown in

Fig. 5, the sheet is applied between the rollers, so that its corrugations match the tongues and grooves of the rollers, and then is forced or drawn forward until the circular or cylinder bend from the front to the rear end of the sheet is imparted. The sheet rolls round the upper roller as the bending proceeds, and when it is fully bent it has the form of that roller if permitted to take that form; but, as it is desirable to remove the cylindric article without removing the rollers, I so control the sheet as to prevent the two ends or edges closing together. The article is removed by moving the rollers from each other and then springing the bent metal off the roller.

What I claim as my invention, and desire to secure by Letters Patent, is—

Bending corrugated sheet metal into the form of a cylinder which is corrugated around its circumference by means of three adjustable rollers having corrugated circumferential surfaces, such as described, said surfaces meshing into one another, and also revolving in concert and with an equal and positive motion, all substantially as herein set forth.

SAML. J. SEELY.
